UNITED STATES PATENT OFFICE.

LAWRENCE GREENWALT, OF FAIRPLAY, WISCONSIN, ASSIGNOR OF ONE-FOURTH TO JOHN WELTER, OF FAIRPLAY, WISCONSIN.

CARTRIDGE-SHELL.

No. 805,012.

Specification of Letters Patent.

Patented Nov. 21, 1905.

Application filed May 16, 1905. Serial No. 260,717.

To all whom it may concern:

Be it known that I, LAWRENCE GREENWALT, a citizen of the United States, residing at Fairplay, in the county of Grant and State 5 of Wisconsin, have invented certain new and useful Improvements in Cartridge - Shells; and I do hereby declare the following to be a full, clear, and exact description of the invention, such as will enable others skilled in the 10 art to which it appertains to make and use the same.

My invention relates to shells or cartridge for use in ordinary common bored guns; and its object is to provide a device of this character 15 having a shot-holder of novel form and arrangement which is adapted to hold the shot until the shell is exploded and to then permit them to leave the holder.

Another object is to provide a shell which 20 will cause the shot to remain close together while being projected, thereby rendering the shell particularly effective in long-range firing.

With the above and other objects in view 25 the invention consists of a shell containing a cap and powder charge, such as usually employed, and within the outer portion of the shell is a cylindrical holder containing shot and which is closed at its outer end by a wad 30 provided for that purpose. The inner end of the holder is open, but separated from the powder charge by wads which serve to separate the shot and powder.

The invention also consists of the further 35 novel construction and combination of parts hereinafter more fully described, and pointed out in the claim.

In the accompanying drawings I have shown the preferred form of my invention.

40 In said drawings, Figure 1 is a perspective view, partly in section, of my improved shell, Fig. 2 is a view, partly in elevation and partly in section, showing the shell. Fig. 3 is a detail view of the shot-holder.

45 Referring to the figures by numerals of reference, 1 is a shell formed of paper or other suitable material and having a powder charge 2 within the inner end thereof. Wads 3 are located upon the powder charge, and abut-

ting these wads is the open end of the cylindrical holder 4, filled with shot 5. This holder is preferably formed of paper, and its outer end is crimped, as at 6, to retain a wad 7 within the outer end of said holder and which serves to close the same. The entire 55 holder is retained in place by crimping the shell, as shown at 8, and this end of the shell and the holder are preferably glued so as to hold them against displacement as a result of ordinary usage. 60

When the shell, such as herein described, has exploded, the holder 4 is projected, as is obvious, and after traveling a short distance turns around and permits the shot 5 to leave through its open end and continue onward in 65 a compact mass. The shot will remain comparatively close at all times during their travel, and the shell is therefore particularly adapted for long-range firing. It will be understood, of course, that the holder 4 can be 70 filled with any kind of shot.

In the foregoing description I have shown the preferred form of my invention, and I do not limit myself thereto, as I am aware that modification may be made therein without 75 departing from the spirit or sacrificing the advantages thereof, and I therefore reserve the right to make such changes as fairly fall within the scope of my invention.

Having thus fully described my invention, 80 what I therefore claim is new, and desire to secure by Letters Patent, is—

The combination with a shell and an explosive charge therein, said shell being crimped at its open end; of a shot - holder 85 crimped at one end and located within the shell, a wad within the holder and retained within the outer end thereof by the crimped portion of the holder, and a wad interposed between the open end of the holder and the 90 explosive charge.

In testimony whereof I have signed my name to this specification in the presence of two subscribing witnesses.

LAWRENCE GREENWALT.
